UNITED STATES PATENT OFFICE

2,176,645

CONCENTRATING APPARATUS

Harry F. Smith, Dayton, Ohio, assignor to General Motors Corporation, Dayton, Ohio, a corporation of Delaware

Original application June 23, 1930, Serial No. 463,085. Divided and this application October 7, 1936, Serial No. 104,489

7 Claims. (Cl. 159—44)

This application is a division of my copending application Serial No. 463,085 filed June 23, 1930, now Patent No. 2,063,960, for Refrigerating apparatus.

5 This invention relates to refrigerating apparatus or air conditioning apparatus, and this application is more particularly directed to an apparatus and method for concentrating a liquid which may be used in refrigerating apparatus, air conditioning apparatus and the like.

10 An object of this invention is to provide an improved method and apparatus for conditioning liquids.

15 Further objects and advantages of the present invention will be apparent from the following description, reference being had to the accompanying drawings, wherein a preferred form of the present invention is clearly shown.

20 In the drawings:

Fig. 1 is a view diagrammatic in its nature, showing an apparatus embodying this invention;

Fig. 2 is an enlarged cross-sectional view of a portion of Fig. 1; and

25 Fig. 3 is an enlarged cross-sectional view of another portion of Fig. 1.

30 The liquid absorbing agent or hygroscopic medium in the chamber 17 of the air conditioning apparatus may be contacted with the air to be conditioned in any suitable manner. Preferably it is contacted with the air by spray device 70 which sprays the liquid absorbent in the air. Eliminators 71 may be provided in order to prevent the carrying of the spray by the air from the chamber 17. The liquid absorbent, which 35 may be calcium chloride, lithium chloride, bromide or iodide, glycerine or the like, is gathered in a sump and carried by the pipe 72 to a device 60 serving alternately as a concentrator or diluter in which water is added or removed from the absorbent as conditions require. From there 40 the liquid absorbent is carried through a pipe 73 to a device 74 serving alternately as a heater or cooler, where the absorbent has the proper temperature imparted to it. From thence the liquid absorbent is carried by the pipe 75 to the pump 76 and from thence to the spray device 70. As will be hereinafter more fully explained, the 45 action in the evaporator or diluter 60 and the heater or cooler 74 is automatically varied in order to impart to the air in the chamber 17 the proper relative humidity at any proper temperature so that when the air is distributed in the rooms 13 and after it has attained the normal 50 temperature to be maintained in the room 13, it will have the desired relative humidity.

For a more detailed description of the construction and operation of the heating and cooling apparatus, reference is hereby made to Patent No. 2,063,960, of which this application is a division.

5 In the summer time, it is generally desirable to remove moisture from the air in the chamber 17. This may be accomplished by suitably concentrating the solution in the device or concentrator 60, suitably cooling the solution in the device or cooler 74 and thereafter spraying the cooled solution in the spray device 70. In order to accomplish this, steam is discharged from the boiler 20 through the pipe 21, coil 22, and returned through the pipe 23 to the boiler 20. The 10 steam passing through the coil 22 is regulated by means of a valve 40 controlled by a thermostatic bulb 40' in the evaporator 60. At the same time water flows from the city water supply 30 through pipe 31 from which it branches through the pipe 33 to the sump 77 and through the coils 32 and waste drain 34. Water also is carried from the city water supply 30 through the pipe 35, coils 36 and pipe 37 to the drain 34 in order to cool the solution in the cooler 74. It is desirable to have the concentrating and cooling action automatic, and for this purpose the valve 40 maintains a substantially constant temperature in the evaporator 60 by controlling the flow of steam through the coil 22. The hydrostatic float 41 is so regulated that it operates the fan 42 by means of a motor 42' which causes air to pass through pipe 86 over the heated solution in the evaporator 60, from thence out through the pipe 87 and is discharged outside of the building. A 15 thermostat 43 preferably placed in the pipe 75 controls the flow of water through the coil 36 so that the temperature of the solution passing from the cooler 74 is maintained at a substantially constant temperature. From this it is to be seen that the air in the summer time first has a definite temperature and relative humidity imparted to it by the solution sprayed from device 70. The heat of absorption is then removed from the air by means of the water coils 32 and thereafter the temperature of the air is further lowered by means of the evaporation of water in the chamber 19. It is to be seen that air may be obtained at ordinary city water temperature and a relatively low humidity or that air may be obtained at relatively high humidity but at a much lower temperature than the city water.

20 In the winter time, a certain amount of moisture is added in the chamber 17 at a suitable temperature, thereafter the air is heated in the 25

chamber 18 by the coils 51 to a sufficiently high temperature to compensate for heat losses of the building. That is, the air must be of sufficiently higher temperature in the ducts 12 so that when 5 the air is discharged in the room 13 it tends to maintain the temperature in the rooms at a certain constant temperature in spite of heat losses through the walls of the building. In order to 10 impart the desired humidity and temperature to the air in the winter, steam flows from the heater 20 through the pipe 50, coils 51 and from thence the condensate flows through pipe 52 back to the heater or boiler 20. Steam also flows through the pipe 21 through the branch 53, coil 54 and from thence the condensate flows through the pipe 23 back to the boiler 20. It is to be understood 15 that the coil 54 preferably is above the level of the liquid in the boiler 20, although it is shown diagrammatically below in order to avoid complications in the drawings. Water from the city supply 30 flows through pipe 31 and from thence to a control 55 into the diluter 60. A constant temperature and concentration of solution is preferably automatically maintained 20 in the device 60. This is accomplished, in the winter time, by causing the hydrostatic float 41 to prevent the action of the fan 42 and to prevent the flow of steam through the coil 22. The hydrostatic float 90 operates to add water 25 through the device 55 in order to compensate for the water evaporated in the chamber 17. The solution then has any predetermined desired temperature imparted to it in the device 14, preferably by causing the thermostat 43 to control by the double valve 44 the flow of steam through 30 the coil 54 and to prevent the flow of water through the coil 36. It is to be understood that different thermostats and independent valves may be provided to control the action of the water in the coil 36 and of steam through the coil 40 54 if desired.

The heater or boiler 20 may provide either steam or hot water as desired, it being understood that when steam is mentioned specifically it may be ordinarily replaced by hot water. The 45 temperature in the heater or boiler 20 is preferably maintained at a constant temperature by providing a thermostat 91 which controls the action of a valve 92 for controlling the combustion in the burner 93. The burner 93 may be a 50 gas burner and may thus be supplied with gas through pipe 94. Air for the combustion of the burner 93 is preferably provided by means of an air duct 110 which is connected to the outside of the building, while the products of combustion are carried by means of the pipe 111 to a suitable chimney also leading outside of the building.

The hydrostatic float 41 may control the action 60 of the fan 42 and also under certain conditions the flow of steam through the coil 22 by any suitable means preferably by electric action. Thus the hydrostatic float 41 actuates a snap switch 97 which starts and stops the motor 42 and operates a magnetic valve 98 for controlling 65 the flow of steam in the coil 22. The snap switch may be of any suitable construction. This hydrostatic float 41 is connected to an arm 99 suitably connected to a Sylphon 100 which is connected to the wall 101 of the evaporator 60. The 70 arm 99 operates through a suitable link 102, the arm 103 of the snap switch 97. Since snap switches are widely known it is unnecessary to describe specifically any type, it being understood that the flow of electric current through 75

the leads 104 is broken by the action of the snap switch 97.

The hydrostatic float 90 controls the addition of water in the winter in order to dilute the solution in the diluter 60. For this purpose the 5 float 90 is connected to an arm 105 which is suitably sealed by means of a Sylphon bellows 106 connected to the wall 101 of the device 60 which thus acts as a diluter. The arm 105 operates a snap link 107 which controls the movement 10 of the valve stem 108 to open and close the valve 55. If desired a suitable Sylphon packing 109 is provided for the stem 108.

When it is desired to use the herein described method or apparatus with the use of a lithium halide salt, the solution may be concentrated and proper temperatures may be imparted to it in accordance with the chart disclosed in the application of Francis R. Bichowsky, Serial No. 457,142, filed May 29, 1930. Under such circumstances it is to be understood that when the solution is to be concentrated in the device 60 the thermostat 40' is regulated so that the steam in the coil 22 imparts to the solution the temperature of the boiling point of the properly concentrated lithium halide solution. Also the thermostat 43 may be regulated to impart to the solution passing through the pipe 75 the proper temperature in order to impart to the air in the chamber 17 the desired relative humidity and 20 temperature as indicated in the chart of the said 25 copending application.

The spraying device 70 may be used to impart the total temperature necessary to the air without the use of the coils 51. Under such conditions the steam coil 54 assumes the entire heating load for the system and must be of a capacity to provide sufficient heat for the entire building. Further if the spray from device 70 is to provide the entire cooling action during the summer time by the elimination of the coil 32, then the 40 water coil 36 must be of sufficient capacity to provide the entire necessary cooling action for the building in the summer time.

The hydrostatic float 41 and the thermostat 40' may be used independently of each other, 45 either being sufficient to accomplish proper concentration. If the float 41 alone is used, it starts the blower 42 and the flow of steam through coils 22 by means of the valve 98 when the solution is insufficiently concentrated and stops the 50 action when the concentration reaches a proper degree. When the thermostat 40' alone is used, a suitable steam escape is provided, such as the pipe 87. The thermostat 40' is regulated to maintain a temperature equal to the boiling 55 point of properly concentrated solution. When the temperature rises above this point the solution is sufficiently concentrated and the flow of steam in coil 22 is stopped by means of the valve 40. When the temperature of the solution does 60 not reach the setting of the thermostat, the solution is under-concentrated and the flow of steam in the coils 22 continues until sufficient concentration is attained.

While the form of embodiment of the invention as herein disclosed, constitutes a preferred form, it is to be understood that other forms might be adopted, all coming within the scope of the claims which follow.

What is claimed is as follows:

1. Concentrating apparatus comprising means forming a flow path for liquid to be concentrated, a heater for liquid in said flow path, a thermostat controlling said heater in accordance with the 75

temperature of heated liquid, a blower circulating a gaseous medium in said flow path in contact with said heated liquid, and means controlling the operation of said blower in accordance with the specific gravity of said liquid.

5. Concentrating apparatus comprising means forming a flow path for liquid to be concentrated, a heater for liquid in said flow path, a motor and blower circulating a gaseous medium in said flow path in contact with said heated liquid, and a switch responsive to the density of said liquid controlling the operation of said motor and blower.

10. Concentrating apparatus comprising means forming a flow path for liquid to be concentrated, a heater for liquid in said flow path, gas circulating means circulating a gaseous medium in contact with liquid in said flow path, and a hydrometer controlled switch controlling the operation of said gas circulating means.

15. Concentrating apparatus comprising means forming a flow path for liquid to be concentrated, a heater for liquid in said flow path, gas circulating means circulating a gaseous medium in contact with liquid in said flow path, and a hydrometer responsive to the density of said liquid controlling the operation of said gas circulating means.

20. Liquid conditioning apparatus for maintain-

ing a hygroscopic liquid at a predetermined concentration comprising flow means forming a flow path for liquid to be conditioned, gas circulating means circulating a gaseous drying medium in contact with liquid in said flow path, diluting means connected to said flow means, and hydrometer means responsive to the density of said liquid controlling the operation of said gas circulating means and said diluting means so as to maintain said hygroscopic liquid at a predetermined concentration.

25. Means for concentrating a liquid comprising, a receptacle for said liquid, means for heating a quantity of said liquid, means for regulating the amount of heat added in accordance with the concentration of said liquid, means for circulating a vapor removing medium in contact with a quantity of said liquid, and means for regulating the circulation of said medium in accordance with the concentration of said liquid.

30. Concentrating apparatus comprising a receptacle for a liquid to be concentrated, a heater for said liquid, means for circulating a vapor removing medium in contact with said liquid, and hydrometer means responsive to the density of said liquid controlling the operation of said heater and said circulating means.

HARRY F. SMITH.
